Primary Examiner — Sandra Snapp*Assistant Examiner* — Bryan N. Melvin(74) *Attorney, Agent, or Firm* — Nitin Kaushik(57) **CLAIM**

The ornamental design for a car smart adapter, as shown and described.

DESCRIPTION

FIG. 1 is a front perspective view of a car smart adapter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The car smart adapter is shown with symbolic breaks in its length. The appearance of any portion of the article between the break lines, in FIGS. 1-6, forms no part of the claimed design.
